FOLDABLE EMERGENCY WARNING SIGNAL

Peter E. Brady, Willowdale, Ontario, Canada, assignor to
Dominion Auto Accessories Limited, Toronto, Ontario,
Canada

Filed Jan. 17, 1975, Ser. No. 541,847

Term of patent 14 years

Int. Cl. D10—06

U.S. Cl. D10—111

FIG. 1 is a perspective view of a foldable emergency warning signal showing my new design.

FIG. 2 is an enlarged fragmentary perspective view thereof showing the top locking mechanism in a detached condition.

FIG. 3 is a perspective view of the same in a folded condition.

FIG. 4 is an enlarged side view of the base in an unfolded condition.

The faceting indicating a reflective surface is partially shown in FIGS. 1, 2 and 3 for convenience of illustration, it being understood that the faceting is uniformly continuous over the areas indicated. The opposite face of the signal is identical to that of the face shown. The signal is fragmentarily shown in FIGS. 2 and 4 for convenience of illustration.

I claim:

An ornamental design for a foldable emergency warning signal, as shown and described.
